DESIGN FOR A DESK

Frank P. Fletcher, Pasadena, Calif., assignor to Fletcher Aviation Corporation, Pasadena, Calif., a corporation of California

Application September 15, 1945, Serial No. 122,101

Term of patent 14 years

(Cl. D33—7)

To all whom it may concern:

Be it known that I, Frank P. Fletcher, a citizen of the United States, residing at Pasadena, in the county of Los Angeles and State of California, have invented a new, original, and ornamental
Design for a Desk, of which the following is a specification, reference being had to the accompanying drawing, forming part thereof.

Referring to the drawing,

Fig. 1 is a perspective view of a desk illustrating my new design;

Fig. 2 is a top plan view thereof;
Fig. 3 is a side-elevational view thereof;
Fig. 4 is a bottom plan view thereof;
Fig. 5 is a front-elevational view thereof; and
Fig. 6 is a rear elevational view thereof.

I claim:

The ornamental design for a desk, as shown.

FRANK P. FLETCHER.
